UNITED STATES PATENT OFFICE.

OZRO C. LANPHEAR, OF GALESBURG, ILLINOIS.

DESIGN FOR A PIN, BROOCH, CHARM, FOB, OR SIMILAR ARTICLE OF JEWELRY.

43,503.

Specification for Design.

Patented Feb. 4, 1913.

Application filed October 9, 1912. Serial No. 724,851. Term of patent 14 years.

To all whom it may concern:

Be it known that I, Ozro C. LANPHEAR, a citizen of the United States, residing at Galesburg, in the county of Knox and State of Illinois, have invented a new, ornamental, and original Design for a Pin, Brooch, Charm, Fob, or Similar Article of Jewelry, of which the following is a specification, reference being had to the accompanying drawing, forming part thereof.

The figure is a plan view, showing my new design.

I claim:

The ornamental design for a pin, brooch, charm, fob or similar article of jewelry, as shown.

OZRO C. LANPHEAR.

Witnesses:

A. B. HAWKINS,
A. O. LINDSTRUM.
